UNITED STATES PATENT OFFICE.

WILLIAM O. FOWLER, OF WENATCHEE, WASHINGTON.

FIXTURE-PLATE.

1,035,782.

Specification of Letters Patent. Patented Aug. 13, 1912.

Application filed April 15, 1911. Serial No. 621,324.

To all whom it may concern:

Be it known that I, WILLIAM O. FOWLER, a citizen of the United States, residing at Wenatchee, in the county of Chelan and State of Washington, have invented new and useful Improvements in Fixture-Plates, of which the following is a specification.

This invention relates to a fixture plate for electric fixtures and brackets, and the object of the invention is to provide a plate adapted to be positioned to surround the hole through which the electric wires are passed, the said plate having means whereby the usual "crow-foot" carrying the wire conducting pipe may be readily secured to the said plate and adjusted so as to direct the wire conducting pipe at the desired angle to the plate and to the wall to which the plate is secured.

With these objects in view, and others which will appear as the nature of the description progresses, the invention resides in the novel construction and arrangement of parts hereinafter fully described and claimed.

In the accompanying drawings, there has been illustrated a simple and preferred embodiment of the improvement, and in which drawings—

Figure 1 is a perspective view of the fixture plate. Fig. 2 is a top plan view of the plate with the "crow-foot" secured therein. Fig. 3 is a sectional view upon the line 3—3 of Fig. 2.

Like numerals of reference denote corresponding parts throughout the several views.

In the drawings, the numeral 1 designates the fixture plate. As illustrated in the drawings, the plate preferably comprises a rounded member having a centrally arranged preferably circular opening 2. The plate is provided with a plurality of counter-sunk openings 3, the same being adapted for the reception of the usual securing screws, whereby the plate may be connected with the wall or ceiling to which the electric bracket or fixture is to be attached. The central rounded opening 2 of the plate is adapted to align with the opening through which the electric wires connected with the

fixture are passed. The plate is further provided with a plurality of angularly arranged threaded elements 4. These elements are preferably positioned intermediate of the counter-sunk openings and the said elements are each provided with a securing nut 5 and a binding nut 6.

The numeral 7 designates the casting which is known to the trade as a "crow's-foot." The "crow-foot," as is well known, is provided with off-set legs having suitable openings, and is further provided with a bulging body portion having threaded apertures to which the wire conducting pipes are attached. The threaded openings of the legs of the "crow-foot" are adapted to receive the threaded elements 5 of the plate 1, and it will be noted that by adjusting the retaining and binding nuts, the angle at which the wire conducting pipes may be easily and quickly regulated, and the said pipe sustained in such a position.

From the above description, taken in connection with the accompanying drawings, the simplicity of the device, as well as the advantages thereof will, it is thought, be perfectly apparent to those skilled in the art to which such inventions appertain. It will be noted that the chances of twisting the wires and causing a short circuit will be entirely obviated and that danger of the plaster from the walls dropping in the canopy of the fixture and the scrapping of the casing of the fixture when the canopy is shoved up the wall or ceiling is also entirely obviated, and that the plate affords a solid and substantial connection between the "crow-foot" and the fixture.

Having thus fully described the said invention, what I claim is:

In a device for the purpose set forth, and in combination with a "crow-foot" provided with offset legs having threaded openings a plate having a central opening, said plate being further provided with counter-sunk openings adapted for the reception of sustaining elements, said plate having a plurality of concentrically arranged spaced threaded extending members, each of said threaded members being provided with a

locking nut and a binding nut, and each of said threaded members adapted to receive the threaded openings of the legs and have its binding and holding elements contact 5 with the opposite faces of the said legs, substantially as and for the purpose set forth.

In testimony whereof I affix my signature in presence of two witnesses.

WILLIAM O. FOWLER.
